WRITING MACHINE

Beulah Louise Henry, New York, N. Y.

Application March 12, 1931, Serial No. 521,912

9 Claims. (Cl. 197—153)

This invention relates to writing machines and has for an object to provide an improved device for use in producing a plurality of copies each having the appearance of a so-called original 5 ribbon copy.

The invention has been developed in connection with the production of a typewriter attachment carrying an ink impregnated ribbon arranged to be interposed between successive sheets 10 of paper opposite the position of operation of the usual type bars and such an embodiment will be more particularly described for the purpose of illustrating the principles of the invention. It will be understood, however, that the description of 15 the particular device is illustrative merely and is not intended as defining the limits of the invention.

It is a feature of the preferred embodiment of the invention that the attachment constitutes a 20 separate unitary structure which can be applied as a unit to a standard fully equipped typewriter and when not required for use it can be readily removed as a unit.

It is also a feature of the invention that the 25 ribbon support can be conveniently adjusted either to operative position for use or inoperative position to permit use of the typewriter without use of the device for making multiple copies.

For the purpose of effecting this invention, 30 there has been provided an assembly which, as a unit, may be attached to a typewriter, or similar machine, so that an inked ribbon carried thereby will be positioned for co-action with paper, or similar material for receiving an inscription, fed 35 into, or positioned in, the machine, and the writing elements of the machine. The ribbon is intended for use either in conjunction with the ribbon ordinarily arranged upon such machine, or without such ribbon. In the specific embodiment of the invention hereafter to be described, 40 the assembly is so associated with the machine that the new ribbon extends substantially the entire length of the platen, and is suspended directly between the platen and the type-bars. While 45 the ribbon will be shown capable of being fed back and forth in front of the platen, it is to be understood that, the invention is not limited to this particular arrangement. By feeding the ribbon longitudinally of the platen, and returning it, 50 it is possible to dispose, between the ribbon sections, so produced, a plurality of sheets of paper, fed by the platen, so that a portion of paper will be disposed to receive the original impact from one ribbon, and to transmit the pressure, arising 55 from this impact, to successive sheets beneath

the original sheet, to effect the production, on such other sheets, from the other portions of the ribbon, of an inscription, identically the same as the original inscription.

The assembly is so related to the machine that 5 it may be moved vertically toward, and away from, the writing position, so that the ribbon may be made effective, or ineffective, at will, as desired. The assembly includes mechanism for feeding the ribbon longitudinally of the platen at 10 a predetermined stage in the movement of the platen relatively to the type-bars. Preferably, this mechanism is so devised that the movement will be effected when the carriage is being returned to the beginning of a new line, in order 15 that movement of the ribbon will not be effected at any time that the type-bars might be effective to produce an imprint. The apparatus for feeding the ribbon is arranged so that the feed of the ribbon may be changed at will, that is, it may 20 be reversed, or, if desired, made ineffective.

The ribbon carrying and feeding means is assembled on the writing machine so that it is immediately accessible for changing ribbons, or for adjustment thereof during the operation of the 25 machine. The ribbon is disposed so that it will feed downwardly toward the writing machine; it is diverted and twisted from its original plane of movement so as to cooperate with the platen and the type-bars.

The invention, however, is not intended to be restricted to the particular construction and arrangement of parts, nor to the particular application of such constructions, nor to the particular mode of operation, nor to the various steps or details thereof, herein shown, as the same may be modified in various particulars, or be applied in many varied relations, without departing from the spirit and scope of the invention, the particular illustration and description going only so far 40 as is necessary to illustrate an operative embodiment by which the invention might be carried out.

On the drawings.—

Fig. 1 is a view in perspective of a portion of a 45 typewriting machine, illustrating the manner of embodying the invention therein.

Fig. 2 is a front elevational view of the ribbon positioning and moving means, embodying the 50 invention, the housing being partially broken away to disclose the interior of the latter.

Fig. 3 is a plan view of the apparatus, a part of the housing being broken away to disclose the arrangement of the ribbon rollers therein.

Fig. 4 is a side elevational view of the apparatus, as seen from the line 4—4 of Fig. 2.

Fig. 5 is a vertical sectional view, on the line 5—5 of Fig. 2.

5 Fig. 6 is a view in perspective, illustrating the manner of application for the invention to the simultaneous production of a plurality of copies.

Fig. 7 is a view, on the line 7—7 of Fig. 3, illustrating details of the operating mechanism.

10 Fig. 8 is a perspective view of a detail of the invention.

Fig. 9 is a perspective view of another detail of the invention.

Fig. 10 is a sectional view on the line 10—10 of 15 Fig. 4.

In the embodiment of the invention shown in the drawings there is represented, at 10, a portion of a typewriter, which may be of any conventional construction. Upon this typewriter has 20 been assembled the ribbon positioning and feeding means 12. Typewriter 10 may have associated therewith a pair of spools 14 and 16 of any conventional or desired type, the ribbon 18, which is to be fed past a ribbon vibrator 20, positioned at the writing point 22, being wound upon such spools. The type-bars 24, only portions of which are shown, are intended to be driven up to a point 22, where they will impact against the ribbon, whereupon an imprint will be produced 25 upon a paper sheet, retained upon platen 26 in the customary manner. Paper fed by the platen is intended to cooperate with a paper support 28 and to be guided by means of a line scale 30 and a finger 32 so as to be brought accurately into 30 position relative to the ribbon for the action of the type-bars.

Means 12 is intended to position a ribbon 34 between the vibrator and the platen for purposes which will be made to appear more clearly hereinafter. The means includes a frame 36, comprising a pair of posts 38 and 40, assembled upon the carriage 42 with which the platen is associated. The posts provide uprights along which the end brackets 44 and 46 may be slid. Between these brackets extend brace bars 48 and 50, assembled as hereinafter appears.

On one of the brackets is fixedly arranged a housing 52 within which are assembled ribbon spools 54 and 56 about which ribbon 34 is wound 50 and unwound during the operation of the apparatus. Guide means 58 and 60 are provided upon brackets 44 and 46 to position ribbon 34 in its effective relation relatively to the platen, the paper and the type-bars, when the machine is used. In order to feed the ribbon at predetermined 55 intervals during the operation of the machine, the positively driven means 62 is provided to effect the rotation of the spools in accordance with the setting of a clutch mechanism 64.

60 Posts 38 and 40 preferably consist merely of rounded portions having threaded reduced ends 66 and 68, whereby the same may be associated with threaded recesses 70 provided upon carriage 42. Preferably a transverse opening 72 is provided in each of the posts for the reception of a tool, by means of which the posts may be more securely locked in position in recesses 70. A screw head 74 may be provided at the upper end of each of the posts for engagement by a screw driver bit in order more readily to associate the 65 posts with the carriage.

70 Brackets 44 and 46 are substantial, and preferably, metal stampings. Bracket 44 may be formed by stamping a portion of metal to provide an upper ear 76 Fig. 8 and a lower self 78; the latter

may have an outwardly projecting, and downwardly turned arm 80. Aligned openings 82 are formed in ear 76 and shelf 78 for the reception therethrough of post 38.

At the other extremity of frame 36 is positioned bracket 46 Fig. 9 which may likewise be a metal stamping having an ear 84 and a shelf 86. A pair of aligned openings 88 may likewise be provided through ear 84 and shelf 86 for the reception therethrough of post 40.

10 Each of the brackets has provided, in the vertical walls 90 and 92 thereof, a pair of openings 94 and 96. The ends of brace bars 48 and 50 are received in these openings and are headed over, or riveted, to retain the brackets firmly, yet slightly 15 flexibly, associated. Frame 36, including brackets 44 and 46, as stiffened by bars 48 and 50, is intended to be movable vertically along the posts, at will, as it is desired to move ribbon 34 into, and out of, position relative to writing point 22. In 20 order to retain the ribbon positioning and feeding means 12 fixedly related to the writing position at the time ribbon 34 is intended to be positioned for use, a notch 98 may be provided in post 40, with which may co-act a finger 100 of a 25 lever 102, pivoted upon a portion of bracket 46. The lever is normally urged into cooperation with the notch by a spring 104, bearing against a portion of bracket 46 and the lever for this purpose. A thumb piece 106 is provided to permit actuation 30 of the lever to release the frame for movement upwardly. By pressing against bars 48 and 50, the frame may be moved downwardly, until the finger engages within notch 98, whereupon the frame will be anchored with relation to writing point 22 35 so that the ribbon may properly coact with the type-bars.

35 In association with bracket 44 and its post 38, there is provided a member 108, Fig. 2 U-shaped in cross section, and substantially of the length 40 of wall 90. Secured to this member in any desired manner, at the cross arm thereof, is a flat spring 110. When member 108 is positioned between ear 76 and shelf 78 so as to be capable of 45 engaging post 38 within the cavity 112 of the U-section, this spring will force the member into contact with the post and tend to force bracket 44 away from the post, thus assuring a desired frictional engagement between post and bracket which will resist unwarranted movement of 50 means 12 relative to point 22. Openings 82 preferably are of substantially larger diameter than post 38 to permit slight play of the post within these openings, so that the spring may function 55 properly for the purposes set forth.

55 Bracket 46 has formed thereon a pair of lugs 114 and 115, which are intended to provide means for securing thereto housing 52. This housing may be made of sheet metal, pressed or stamped so as to provide a rear wall 118 which is secured 60 against lugs 114 and 115 by any desired means. When so secured, there is provided a pair of aligned openings 120 and 122 in lug 114 and an additional lug 116, parallel to lug 114, for the reception therethrough of a shaft 124 upon which 65 spools 54 and 56 are mounted, in the manner hereinafter more specifically described.

65 Associated with lug 114 and wall 118 of the housing, at the opening 120, is a bearing 126; such bearing may be formed from a bushing, inserted 70 through openings in the rear wall and the lug, and then headed over, to assure its firm retention relative to the bracket 46 and the housing. At lug 116, in like manner, there may be asso- 75

ciated another bushing to provide bearing 128, which, together with bearing 126, provides the support and retaining means for shaft 124.

Affixed to the outer end of the shaft is a finger member 130, intended to be gripped by the fingers of the operator to move the shaft rotationally or longitudinally, for purposes either of feeding the ribbon manually, when so desired, or of setting the ribbon feeding means to drive the ribbon in either direction or in non-feeding position, as desired.

Each of the spools 54 and 56 is of substantially the same construction as spools now generally in use upon machines of this character. Each spool 15 may consist of a circular plate 132 and a dished plate 133, the dished portion of which provides an axle or hub member 134, upon which the ribbon is wound, and retaining the plates in separated relation. With each of the hub members is provided a portion 135 having a groove 136. The hub member is provided with a bore 138 sufficient to permit the spools, unless otherwise restrained, free rotation upon shaft 124, upon which they are intended to be assembled. On shaft 124, there is 20 provided a pin 140, fixedly associated with the shaft, and having the end portions thereof extending beyond the shaft in such relation that, if the shaft be pulled so as to draw it out of the housing, pin 140 would be brought into groove 30 136, engaging spool 54, and driving the same, as shaft 124, rotates, to feed the ribbon.

Finger member 130 is formed so that it may be removed readily from the shaft end so that the ribbon spools may be interchanged to renew the 35 ribbon, or for similar purposes. The member is formed, for this purpose, with a threaded portion receivable over the threaded end 144 of the shaft. Since the shaft is intended to be rotated in one direction only, and normally is restrained against 40 other rotation, the manner of threading is preferably such as to tighten the grip of the threads when attempt is made to rotate the shaft in its intended direction, and to thread the finger piece off the shaft when reverse movement is attempted. 45 The inner end of the member 130 is formed with one or more lugs 146, preferably a pair, diametrically aligned. These lugs are intended to engage within the groove 136 of the spool 56; this engagement occurs when the shaft is moved into 50 the housing, the lugs then sliding into engaging relation with the groove so as to be capable of driving the spool.

A cover 148 is provided for the housing, and consists of a stamping of any desired metal, and substantially of the contour of the housing. In a front face 150 of the cover is an opening 152 of sufficient extent to permit the protrusion of finger member 130. This cover may be retained upon the housing by the cooperation of a pair of pins 154 with a pair of bayonet slots 156 in the flange 158, the cover being intended to be slid over the housing, and then, by a slight rotative movement, to have the slots engage over the pins and under the heads thereof. To permit the association of the cover with the housing, by the rotative action described, a portion of the wall of the housing, as at 164, may be cut away.

At opening 152, there is assembled a washer 166 between which, and the wall of the cover, there 70 is positioned a spring washer 170. These elements are retained in relation to each other by a portion of the cover, belled up around the opening. This portion is turned down against washer 166 to retain both washers associated with the 75 cover, yet permitting movement of washer 166,

under the action of spring washer 170, toward, and against, the spool 56, which is intended to be frictionally engaged by washer 166 during the operation of the apparatus, the bell extending into the dished portion of the plate 133 of spool 56.

In like manner, a spring washer 174 is assembled upon the rear wall of the housing, at the opening therethrough, to coact with spool 54. A washer 176 is positioned between spools 54 and 10 56 to maintain them in spaced relation, and also to reduce the frictional engaging surfaces of these members, to facilitate their relative rotational movement. The assembly of washer 174 upon the housing is accomplished preferably by turning 15 over the end of bearing 126 rather than by working the metal of the housing itself, although this also may be done, if desired.

By the arrangement of washers 166, 174 and 176, when the cover 148 is assembled upon the 20 housing, the ribbon spools will be retained upon the shaft 124, being permitted but slight longitudinal movement against the action of washers 166 and 174. Washers 166 and 174 actually apply a frictional drag against their respective 25 ribbon spools, preventing slack in the ribbon as it is wound and unwound. When the housing cover is removed, and the finger piece removed, both ribbon spools may be removed from the shaft.

Bearing 128 is formed with a drilled aperture 30 178 Fig. 10 in which is housed a ball 180, retained in position by a split spring washer 182, which is seated within a recess 184 in the bearing. The ball, as part of clutch mechanism 64, is intended to cooperate with a number of circumferential 35 grooves 186, preferably three in number, and arranged so that, in one position, shaft 124 will be retained so that pin 140 cooperates with ribbon spool 54, in its next position, pin 140 will be out of engagement with spool 54, and lugs 146 will 40 have been advanced toward spool 56, but will not have engaged such spool, and in the next successive position, the lugs will be brought directly into engagement with spool 56 so that the latter may be driven from shaft 124. Collars 190 and 45 192 are provided to limit the movement of the shaft with relation to the assembly, the collar 190 being adapted to engage bearing 128, while collar 192 will engage lug 116.

In order to effect feeding movement of the ribbon relative to the platen, drive means 62 Figs. 3 and 7 is provided and is effective to rotate the shaft 124 in one direction. As has been pointed out, the relation of the shaft to the spools is such that but one only of the spools may be rotated at 55 one time; this selective rotation, by the arrangement of the ribbon upon its guiding means, makes it possible, by manipulating the finger piece, to control the direction of feed of the ribbon as desired.

Drive means 62 may consist of a ratchet wheel 194, keyed to shaft 124, and operated by a pawl 196, carried upon a pawl carrier 198. The wheel and the pawl carrier partially extend through a slot 200, formed in bracket 46, and are thus retained against longitudinal movement along the shaft. The pawl carrier is mounted pivotally upon the hub 202 of the ratchet wheel, and at one extremity thereof has secured a bushing 204, retained by such means as screw 206. Wound around the bushing is a spring 208, one end of which bears against the pawl carrier, and the other end of which is anchored within an opening in the pawl 196 so that the latter is retained 60 65 70 75 76 pressed against the teeth of wheel 194.

The other end of the carrier is off-set, as at 210, to clear a vertically movable rod 212, Fig. 4 a pin 214 upon which engages within a slot 216 in the off-set end. The rod is substantially 5 square in cross section at its lower extremity, and passes through an opening 218 in shelf 86. The opening is also square in cross-section, cooperating to retain the rod against rotational movement, and to retain pin 214 properly related to 10 slot 216, at all times. At the upper end of the rod, there is formed a reduced portion 220, which passes through ear 84 to align the rod with opening 218. Received between the ear and a washer 222, seated upon the shoulder between the reduced portion and the body of the rod, is a spring 224, acting normally to push the rod downwardly. A collar 226 on the outer end of portion 220 limits 15 downward movement of the rod.

At the lower extremity of the rod, there is pivotally mounted a finger 228, the end of which carries a roller 230. At the pivot of the finger, there is provided a lug 232 which cooperates with a surface 234 at the end of the rod, the relation 20 of lug and surface being such that the finger 25 will be permitted substantial rotation out of a vertically aligned relation with the rod, in one direction only. A camming surface 236 may be provided at any point along the body of the typewriter, which remains stationary, relatively to 30 the carriage, at all times during the operation of the machine. The surface is intended to be in such position that roller 230 would ride over it at some interval in the operation, or movement, 35 of the platen.

The roller, in engaging the surface 236, in movement in one direction, will merely pivot away from the surface so as to ride freely over it. In movement in another direction, however, the cooperation of lug 232 and surface 234 will force 40 the roller to move vertically, in aligned relation to rod 212, and thus to effect vertical movement of the rod against the action of spring 224. During this movement, the pawl carrier will be rocked to actuate the pawl 196, sliding it over the teeth 45 of the ratchet wheel. When the roller has passed beyond the surface 236, return of the rod, under the action of its spring, will cause positive driving of wheel 194 as the pawl engages its teeth.

For the purpose of restraining the wheel against 50 unwarranted movement, when the rod is moving upwardly, there is provided a spring finger 238, secured to a wall of the housing, and bearing against the teeth of the wheel at all times. The finger is located so that the wheel may rotate 55 only in the direction in which the pawl 196 is intended to actuate it. The wheel will thus be retained against any unwarranted movement throughout the operation of the apparatus.

The surface 236 and the roller 230 preferably 60 are so located that they will be inactive to produce any movement of the ribbon except after a line of writing has been completed, and the platen is being moved backwardly to start a new line. In this manner, no movement of the ribbon 65 relatively to the sheet is produced at any time that a writing element might be brought into active relation with such sheet. As can be seen, provision is herein made whereby the ribbon remains stationary throughout the movement of 70 the platen as the type-bars are active. In other words, a new ribbon portion is presented for each successive impact of a type-bar against the paper sheets upon the platen. Variations of the particular feeding means obviously may be made 75 and provision may be made, by a plurality of

surfaces 236, to secure a number of actuations of the ribbon during any single movement of the carriage.

Forming a part of shelf 86 is an extending arm 240 with which is associated a bracket 242, preferably secured to the rear wall of the housing and intended to brace arm 240. Secured to the cooperating ends of the arm and bracket is the guide means 58, including the turning piece 244. This piece is preferably a portion of solid metal, 10 formed with a suitable recess 246 for the reception of the ends of the arm and bracket. Piece 244 is formed with a pair of converging faces 248, the angle of the faces to the vertical being approximately 45°. 15

Shelf 78 has an arm 80 so related thereto that a roller 250, forming part of the guide means 60, and retained in vertical position between an ear 252 and a lug 254, struck up from the arm, will be positioned substantially in alignment with the 20 position of a pair of pins 256. These pins are carried upon an extending seat 258 preferably formed integrally with turning piece 244. It is intended that the ribbon from spool 56 shall be guided down through the open bottom of the 25 housing, and be brought into engagement with, and turned around a face 248, then to be wound past a pin 256, carried around the roller 250, then back around the other pin 256, over and around the other face 248, to the spool 54. The 30 ribbon, in its use, will by this means, first be disposed with its plane practically perpendicular to the surface of a portion of paper or the like retained by the platen of the typewriter. Then, by means of the turning piece and the associated 35 pins and the roller, it will be twisted around into a plane substantially parallel to that of the paper. Also, instead of a single ribbon being disposed between the paper and the type-bars, there will be two distinct ribbons so positioned, 40 for purposes which will be more fully described hereinafter. These two ribbons will be disposed substantially in coincidence, insofar as the paper with which they are to cooperate is concerned. The number of copies produced by this apparatus may be varied in accordance with the 45 number of turns of the ribbon, these turns being produced merely by the provision of additional pins and rollers.

In order to produce a plurality of copies, upon 50 a machine using this invention, it is first necessary to move means 12, as a unit, downwardly, to position the ribbon at the writing position. When the ribbon is thus located, the sheets of paper, fed around the platen, may then 55 be manipulated so that, as shown in Fig. 6, a ribbon will be disposed between two successive sheets of paper. In one desired instance, a sheet of paper may be positioned in back of one turn 260 of the ribbon, while the other ribbon turn 60 262 will be positioned between two other successive portions of the paper. Then, by manipulating the type-bars 24 to strike the paper and the ribbons, associated in the manner indicated, imprints upon all the sheets of paper will be produced, each of the imprints being exactly the 65 same, and each of the imprints being a permanent ink impression. Some of these impressions will be produced on the back face of a sheet; however, by using a translucent or transparent 70 material for the sheet, the imprint will be made clearly visible on the front face of the sheet.

As each type-bar becomes effective, the carriage moves relatively to the writing point in the customary manner. When a line of writing is 75

finished, the platen is manipulated to position the sheets of paper to have imprinted thereon a new line of writing. The sheets feed freely, without smudging, through the suspended ribbon turns, 5 which remain stationary. The ribbon, therefore, need be only as wide as one line of writing in order to accomplish the desired results.

Many other changes could be effected in the particular apparatus designed, in the methods of 10 operation set forth, and in the specific details thereof, without substantially departing from the invention hereof which is intended to be defined in the accompanying claims, the specific description hereinabove being set forth merely to illustrate an operative embodiment for carrying out 15 the spirit of the invention.

What is claimed as new and useful is:—

1. In combination with a writing machine having a plurality of impact writing elements and a 20 paper receiving and retaining member, the member and the elements being relatively movable to make the elements capable of writing on paper retained by the member along a line selected at will, a pair of supports extending vertically from 25 the member and in spaced apart relationship along the member in the direction of the line of writing, a frame slidably carried by the supports for movement toward and away from the member, extensions from the frame adjacent each end 30 thereof, one of the extensions having a guide plate mounted thereon, and turning pins on each of the extensions, the plane of the plate intersecting transversely a line connecting between the pins.

35 2. In combination with a writing machine having a plurality of impact writing elements and a paper receiving and retaining member, the member and the elements being relatively movable to make the elements capable of writing on paper 40 retained by the member along a line selected at will, a pair of supports extending vertically from the member and in spaced apart relationship along the member in the direction of the line of writing, a frame slidably carried by the supports 45 for movement toward and away from the member, extensions from the frame adjacent each end thereof, one of the extensions having a V-shaped guide plate mounted thereon, and turning pins on each of the extensions, the plane of the plate 50 intersecting transversely a line connecting between the pins.

55 3. In combination with a writing machine having a plurality of impact writing elements and a paper receiving and retaining member, the member and the elements being relatively movable to make the elements capable of writing on paper retained by the member along a line selected at will, a pair of supports extending vertically from the member and in spaced apart relationship 60 along the member in the direction of the line of writing, a frame slidably carried by the supports for movement toward and away from the member, extensions from the frame adjacent each end thereof, one of the extensions having a guide 65 plate mounted thereon, turning pins on each of the extensions, the plane of the plate intersecting transversely a line connecting between the pins, a shaft carried by the frame in a plane extending transversely of the line of writing, a ribbon spool 70 on the shaft, and a ribbon fed from the spool around the pins, the plate acting to change the direction of the ribbon from its disposition on the spool to its disposition between the pins.

75 4. In combination with a writing machine having a plurality of impact writing elements and a

paper receiving and retaining member, the member and the elements being relatively movable to make the elements capable of writing on paper retained by the member along a line selected at will, a pair of supports extending vertically from 5 the member and in spaced apart relationship along the member in the direction of the line of writing, a frame slidably carried by the supports for movement toward and away from the member, extensions from the frame adjacent each end 10 thereof, one of the extensions having a V-shaped guide plate mounted thereon, turning pins on each of the extensions, the plane of the plate intersecting transversely a line connecting between the pins, a shaft carried by the frame in a 15 plane extending transversely of the line of writing, a ribbon spool on the shaft, and a ribbon fed from the spool around the pins, the plate acting to change the direction of the ribbon from its disposition on the spool to its disposition between 20 the pins.

25 5. In combination with a writing machine having a plurality of impact writing elements and a paper receiving and retaining member, the member and the elements being relatively movable to make the elements capable of writing on paper retained by the member along a line selected at will, a pair of supports extending vertically from 30 the member and in spaced apart relationship along the member in the direction of the line of writing, a frame slidably carried by the supports for movement toward and away from the member, extensions from the frame adjacent each end thereof, one of the extensions having a V-shaped guide plate mounted thereon, 35 turning pins on each of the extensions, the plane of the plate intersecting transversely a line connecting between the pins, a shaft carried by the frame in a plane extending transversely of the line of writing, a pair of ribbon spools on the 40 shaft, and a ribbon fed from the spools around the pins, the plate acting to change the direction of the ribbon from its disposition on the spools to its disposition between the pins.

45 6. In combination with a writing machine having a plurality of impact writing elements and a paper receiving and retaining member, the member and the elements being relatively movable to make the elements capable of writing on paper retained by the member along a line selected at will, a pair of supports extending vertically from 50 the member and in spaced apart relationship along the member in the direction of the line of writing, a frame slidably carried by the supports for movement toward and away from the member, extensions from the frame adjacent each end thereof, one of the extensions having a V-shaped guide plate mounted thereon, turning pins on each of the extensions, the plane of the plate intersecting transversely a 55 line connecting between the pins, a shaft carried by the frame in a plane extending transversely of the line of writing, a pair of ribbon spools on the shaft, and a ribbon fed around the pins from one 60 spool back to the other spool, the plate acting to change the direction of the ribbon from its disposition on the spools to its disposition between the pins.

65 7. In a typewriting apparatus, the combination with a fully equipped typewriter carriage of a pair of upright posts secured to the typewriter carriage, a unitary rigid frame vertically adjustable on said posts, an impression ribbon carried by said frame and movable to and from 70 op- 75

erative position upon vertical movement of said frame, means for securing said frame in adjusted position relative to said posts and means actuated by longitudinal movement of the carriage 5 for feeding the ribbon.

8. A typewriter attachment for use in making a plurality of duplicate ribbon copies comprising a frame attachable as a unit to a longitudinally movable typewriter carriage, a pair of 10 ribbon spools mounted co-axially and closely adjacent at one end of said frame, a longitudinally movable vertical rod mounted adjacent said ribbon spools and engageable with a cam on the typewriter frame during longitudinal movement

of the carriage and means actuated by said vertical rod for rotating one of said ribbon spools.

9. A typewriter comprising, in combination, a main frame, a cam on said main frame, a platen and platen carriage reciprocably mounted on said main frame, a frame mounted on said carriage, a pair of ribbon spools mounted co-axially on said second-mentioned frame, a vertical rod mounted on said carriage and engageable with said cam to be moved vertically thereby upon 10 reciprocation of the carriage and means actuated by vertical movement of said rod for rotating one of said spools.

BEULAH LOUISE HENRY.
